UNITED STATES PATENT OFFICE

92,097

DESIGN FOR A RUG

Charles Lehner, New York, N. Y., assignor to Bigelow Sanford Carpet Co., Inc., a corporation of Massachusetts

Application October 25, 1933, Serial No. 49,553

Term of patent 7 years

To all whom it may concern:

Be it known that I, CHARLES LEHNER, a citizen of the United States, and resident of New York, in Queens County and State of New York, have invented a new, original, and ornamental Design for a Rug, of which the following is a specification, reference being had to the accompanying drawing, in which a plan view of the rug is shown.

I claim

The ornamental design for a rug substantially as shown.

CHARLES LEHNER.
